C. H. JARVIS

DISPLAY BASKET OR RECEPTACLE

Filed Oct. 7, 1922

By *Chappell & Card*
Attorneys

UNITED STATES PATENT OFFICE.

CHARLES H. JARVIS, OF BATTLE CREEK, MICHIGAN, ASSIGNOR TO UNITED STEEL AND WIRE CO., OF BATTLE CREEK, MICHIGAN.

DISPLAY BASKET OR RECEPTACLE.

Application filed October 7, 1922. Serial No. 593,131.

To all whom it may concern:

Be it known that I, CHARLES H. JARVIS, a citizen of the United States, residing at Battle Creek, county of Calhoun, State of Michigan, have invented certain new and useful Improvements in Display Baskets or Receptacles, of which the following is a specification.

This invention relates to improvements in display baskets or receptacles.

The main object of the invention is to provide an improved display basket or receptacle for the use of merchants which is effective for display purposes and is attractive in appearance and strong and durable although light in weight.

Further objects, and objects relating to structural details, will definitely appear from the detailed description to follow.

20 The objects of the invention are accomplished by the devices and means described in the following specification. The invention is clearly defined and pointed out in the claims.

25 A structure which is a preferred embodiment of the invention is clearly illustrated in the accompanying drawing, forming a part of this application, in which:

The figure is a perspective view of my improved display receptacle or basket.

I have illustrated in the accompanying drawing a form or embodiment of my invention which has proved highly satisfactory on the market.

35 The basket illustrated is formed entirely of metal, the side and bottom slats 1 and 2 being formed integrally of wire, the hoops 3, 4 and 5 being of wire or rods, the hoops being disposed on the outer side of the slats 40 and secured thereto by electric welding. A center disk 6 is provided which is also of metal, the ends of the bottom slats being welded on the under side thereof. The bottom hoops 3, 4 and 5 are disposed on the 45 outer sides of the slats, the hoop 3 being disposed on the bottom slats adjacent the angles of the slats, the hoop 5 being disposed at the upper end of the slats, while the hoop 4 is disposed in an intermediate 50 position.

I provide three leg members each formed of heavy wire or rod folded upon itself and conformed to an A-shape, providing legs

7 and downwardly diverging braces 8. The bight ends of the leg members are bent laterally, providing feet 9, the apexes of the leg members being secured to the bottom hoop 3 by welding thereto.

The braces 8 are crossed with those of adjacent leg members and welded together at their crossing points 10, the lower ends of the crossed braces being welded at 11 to the hoop members of the legs.

With this arrangement the parts are secured and form a very rigid structure and at the same time the leg members may be formed of comparatively light material and the structure is graceful and attractive in appearance.

Having thus described my invention, what I claim as new and desire to secure by Letters Patent, is:

1. In a display stand, the combination of a metal basket comprising angled slats and a bottom hoop welded on the outer side thereof adjacent the angles, and A-shaped leg members formed of rods folded upon themselves providing legs and downwardly diverging braces therefor, the apexes of said leg members being welded to said bottom hoop, the bight portions thereof being turned laterally providing feet, the braces of adjacent leg members being crossed and welded together at their crossing points, their ends being welded to the side members of adjacent legs.

2. In a display stand, the combination of a metal basket comprising angled slats and a bottom hoop welded on the outer side thereof adjacent the angles, and A-shaped leg members formed of rods folded upon themselves providing legs and downwardly diverging braces therefor, the apexes of said leg members being welded to said bottom hoop, the braces of adjacent leg members being crossed and welded together at their crossing points, their ends being welded to the side members of adjacent legs.

3. In a display stand, the combination of a metal basket comprising a bottom hoop, and A-shaped leg members formed of rods folded upon themselves providing legs and downwardly diverging braces therefor, the apexes of said leg members being secured to said bottom hoop, the bight portions thereof being turned laterally providing

feet, the braces of adjacent leg members being secured to the side members of the legs.

4. In a display stand, the combination of a metal basket comprising a bottom hoop, ⁵ and A-shaped leg members formed of rods folded upon themselves providing legs and downwardly diverging braces therefor, the

apexes of said leg members being secured to said bottom hoop, the braces of adjacent leg members being secured to the side members of the legs. ¹⁰

In witness whereof, I have hereunto set my hand and seal.

CHARLES H. JARVIS. [L.S.]
